UNITED STATES PATENT OFFICE.

NICKOLAS J. ROETHER, OF MINERAL POINT, WISCONSIN.

SPARK-ARRESTER.

1,037,326.

Specification of Letters Patent. Patented Sept. 3, 1912.

Application filed November 17, 1911. Serial No. 660,808.

To all whom it may concern:

Be it known that I, NICKOLAS J. ROETHER, citizen of the United States, residing at Mineral Point, in the county of Iowa and 5 State of Wisconsin, have invented certain new and useful Improvements in Spark-Arresters; and I do hereby declare the following to be a full, clear, and exact description of the invention, such as will enable 0 others skilled in the art to which it appertains to make and use the same.

This invention relates to spark arresters and more particularly to that class of spark arresters adapted for use upon smoke stacks 5 of engines.

An object of the invention is to provide a spark arrester attachment for smoke stacks which will effectively arrest the sparks and prevent escape of the same.

Another object is to devise a spark arrester of this character which may be readily positioned upon the upper end of a smoke stack and which will allow the escape of the smoke, but will prevent the 25 sparks or cinders from escaping and probably causing serious damage.

Another object is to devise a spark arrester of novel form and one which will be extremely effective in the performance of 30 its duties.

Other objects and advantages will be herein after set forth and pointed out in the specification and claim.

In the accompanying drawings which are 35 make a part of this application, Figure 1, is a vertical sectional view through the spark arrester secured upon the upper end of a smoke stack, said view being taken on the line 1-1, Fig. 2; while, Fig. 2, is a similar 40 view, at right angles to Fig. 1, taken on the line 2-2, Fig. 1.

Referring more particularly to the drawings in which similar reference numerals 45 designate corresponding parts throughout the several views, 1 represents the upper end of an ordinary smoke stack over which the inverted V-shaped bottom 2 of the spark arrester housing is secured, a suitable opening being provided through the center of 50 the bottom 2 to accommodate the smoke stack 1, said stack projecting slightly through the bottom 2. The bottom 2 is, preferably made rigid with the upper end 55 of the smoke stack 1 and may, if desired, be formed integral therewith.

The side edges of the converging walls

of the inverted V-shaped bottom 2 are connected to the opposite sides 3 of the spark arrester casing. The lower edges of the slanting portions of the inverted V-shaped 60 bottom 2, however, are directed downwardly as shown at 4, adjacent the smoke stack 1, to meet the horizontal portions 5, some distance below the upper end of the smoke stack. Connecting with the horizontal portions 5, opposite the portions 4, are the lower edges of the sides 6, positioned at right angles to and connecting with the sides 3, above the smoke stack 1. Depending from the lower horizontal portion 5 are 65 the pipes 7, beneath which buckets or other suitable means may be placed to catch soot and the like collected between the walls 4 and 6, it being understood that the valve plates 8, resting upon the horizontal portion 70 75 7 are drawn outwardly to allow the soot to pass downwardly through the pipes 7.

The upper end of the casing is closed by a cover or top 9 secured upon the upper edges of the sides 3 and 6, and depending 80 from the edges of a central opening in the top 9 is a screen 10 which is preferably wedge shaped and has its opposite ends 10' closed by screens. This will prevent any 85 sparks or cinders, reaching the upper end of the casing, from escaping through the central opening therethrough.

Projecting inwardly and downwardly from the inner surface of the side 6, near the upper ends thereof, are the deflecting 90 plates 11.

The sides 6 may be sloped inwardly, as shown at 6', near their upper ends, if desired, and the edges of the sides 3, below the inverted V-shaped central portion 2 of 95 the bottom of the casing, may be converged slightly, as shown at 3', toward the lower horizontal portions 5, upon opposite sides of the smoke stack.

Above the smoke stack 1 are the the opposite disposed hollow cone members 12 and 13, the bases of said cones being disposed in a horizontal plane and secured together by the flanges 12' and 13' respectively. The point of the inverted cone 13 extends into 100 the upper end of the smoke stack 1 and is supported in position by means of the supporting straps 14, having their opposite ends bent and secured to the cone 13 and to the interior of the smoke stack 1, adjacent 105 the upper edge of the latter. Directed outwardly and upwardly from opposite sides 110

of and secured to the upper cone 12 are the baffle plates 15 which are bent to dispose one portion at an angle to the other and converging upwardly. The plates 15 are connected 5 at their lower portions and upon opposite sides of the cone 12 by the integral portion 16.

Thus it will be seen that when this ar-
rester is in use, smoke, sparks and cinders
10 pass out of the upper end of the smoke stack
1 and are guided by the lower cone 13
against the baffle plates 15 which will serve
to retard the same and deflect the sparks and
cinders and cause them to drop between the
15 sides 3 and walls 4 and 6 until they fall upon
the valve plates 8. Should any sparks or
cinders pass around and above the baffle plates 15, they will be thrown against the
under faces of the deflecting plates 11 and
20 by said plates be further interrupted in their
travel toward the upper end of the casing.
Owing to the slant at which the deflecting
plates 11 are directed, any cinders arrested
thereby will readily slide off of said plates
25 and drop downwardly upon the valve plates
8. The smoke will continue upwardly
through the casing and travel out through
the screens 10, which will also serve to pre-
vent any small cinders or sparks, which may
30 succeed in passing the baffle plates 15 and
deflecting plates 11, from escaping through
the upper end of the device.

It will thus be seen that, by using this
35 spark arrester, the sparks and cinders trav-
eling upwardly through the smoke stack will
be prevented from escaping to the atmos-
phere and probably causing a fire or other
serious damage. It will also be evident that,
40 as the lower portions of the casing, between
the portions 4 and side walls 6 and 3, are
filled with cinders and soot, suitable recep-
tacles may be placed beneath the pipe 7 and

the valve plates 8 withdrawn to allow the
cinders and soot to drop downwardly
through the pipe 7 and into the receptacle, 45
thus cleaning the casing. It will also be
evident that this spark arrester may be em-
ployed upon any smoke stack and will be
highly efficient and effective in the perform-
ance of its duties.

Owing to the extremely small number of
parts and the comparatively simple forma-
tion thereof, it will be evident that the spark
arrester may be manufactured at a reason-
able cost and will be substantial in use. 50 55

What I claim is:—

A spark arrester comprising the combina-
tion with a smoke stack, oppositely disposed
cone members having their bases secured to-
gether and disposed in a horizontal plane, 60
and baffle plates secured to the upper of
said cones and disposed upwardly and out-
wardly therefrom; of a casing secured over
the upper end of the smoke stack, said cas-
ing having a screened opening in the upper 65
portion thereof and deflecting plates near its
upper end, said casing depending below the
upper end of the smoke stack and upon op-
posite sides of the latter, an inverted
V-shaped bottom disposed between said de-
pending portions and provided with a cir-
cular opening for receiving said smoke
stack, pipes projecting from said depending
portions, valve plates within said depending
portions to cover the open upper ends of the 70 75
pipes.

In testimony whereof I have signed my
name to this specification in the presence of
two subscribing witnesses.

NICKOLAS J. ROETHER.
